TOY GUN

Vernon D. Howe, Buffalo, N. Y.

Application September 22, 1932, Serial No. 634,403

8 Claims. (Cl. 124—14)

This invention relates to toys and it has particular relation to the type of toy gun in which an elastic missile is adapted to be employed as a projectile.

5 One object of the invention is to provide a toy gun in which a trigger serves as a positive clamping means for one end of an elastic missile and anchoring means is provided at the other end of the missile without interfering with the discharge of the latter from the gun.

Another object of the invention is to provide a toy gun in which a plurality of missiles can be discharged successively.

15 Another object of the invention is to provide a trigger guard and control for facilitating the manufacture and operation of the gun.

In the drawing:

Fig. 1 is a side elevation of a toy gun with portions broken away and shown in cross-section;

20 Fig. 2 is a plan of a missile employed in conjunction with the toy gun;

Fig. 3 is a fragmentary elevation of a toy gun with portions shown in cross-section and illustrating another form of the invention;

25 Fig. 4 is a cross-section taken substantially along the line IV—IV of Fig. 3;

Fig. 5 is a view similar to Fig. 1 and illustrating another form of the invention;

30 Fig. 6 is a view similar to Fig. 3 and illustrating still another form of the invention;

Fig. 7 is a perspective of a trigger employed in the toy gun; and

Fig. 8 is a perspective of a combined trigger 35 guard and spring employed in the gun illustrated in Fig. 3.

Referring to Figs. 1 and 2, a toy gun 10 is shown which simulates the form of an automatic pistol and includes an imitation barrel 11 and butt 40 or handle grip 12. The portion of the gun adjacent the junction of the barrel and butt is provided with an inclined opening or slot 15 in which a trigger 16 is pivotally mounted upon a pin 17 that is supported laterally through the body of the toy. A curved finger fitting portion 18 of the trigger projects below the slot 15 and the upper portion of the trigger has a pointed portion 19 which is adapted to impinge against an upper rear wall portion 20 of the slot 15. It 45 will be observed that the pin is located adjacent the upper end of the trigger to provide favorable leverage with respect to the finger fitting portion 18.

A bore 22 is formed in the handle 12 for receiving a coil spring 23 that has one of its ends

abutted against a plug 25 fixed, as indicated at 26, in the bore and its other end disposed in a socket 27 formed upon the rear side of the trigger. Hence, the trigger under the influence of the spring is always urged in a clockwise direction about the pin 17 as viewed in Fig. 1 and the portion 19 impinges the wall 20.

At the outer end of the barrel 11 a transverse groove 28 is formed and a central longitudinally disposed groove 29 inclines gradually from the upper surface of the barrel into the transverse groove.

An elastic missile 30 having an oblong body portion 32 and an enlarged transverse head 33 arranged to form a T-shape, is adapted to have its head portion anchored in the transverse groove 28 and its body portion stretched along the groove 29 and upon the upper surface of the barrel.

The end portion of the missile opposite the head is inserted between the upper end portion 19 of the trigger and the slot wall 20. Thus

loading or mounting of the missile is accomplished by pressing the trigger to provide a space for receiving the end of the missile between the trigger and wall 20 and then by releasing the trigger the missile is resiliently held in place until it is ready

75 to be discharged. Then by pressing the trigger at the finger fitting portion 18 the missile in snapping back to its normal form is projected outwardly from the end of the barrel 11. It is also convenient to reverse the manner described in load-

ing the gun by first inserting the missile in the portion behind the upper end 19 of the trigger and then stretching it to the end of the barrel

70 where it is anchored in the grooves 28 and 29.

In the form of the invention shown in Figs. 3 and 4, a toy 35 of substantially the same shape as that shown in Fig. 1 includes a barrel 36 and a butt or handle portion 37, and it is provided with a pair of triggers 38 and 39 mounted upon a common pivotal pin 50 extending through the body of the toy.

Suitable inclined slots 52 in the toy adjacent the junction of the barrel and handle portions are provided for receiving the trigger. At the upper end of the trigger 39 a facing

54 of rough material, such as emery, sandpaper or the like, is applied to prevent slipping of a missile clamped by the trigger. A trigger guard 53, composed of resilient material is secured, as indicated at 55, to the butt and barrel portions of the toy and is provided with end spring fingers 56 and 57 which contact and resiliently urge the upper end portion 58 of the trigger against rear wall portions of the slots 52.

100 In this construction a pair of grooves 59 extending from the slots 52 to the end of the barrel terminate in grooved

105 52 to the end of the barrel terminate in grooved

110 52 to the end of the barrel terminate in grooved

105 52 to the end of the barrel terminate in grooved

110 52 to the end of the barrel terminate in grooved

end portions of similar construction to that defined by the grooves 28 and 29 shown in Fig. 1, with the exception that they are double for receiving two missiles 30.

5 It will be observed that the triggers 38 are inclined at different angles or at angles to each other, and consequently, in discharging missiles the trigger 38 is first actuated and then the second trigger 38 is actuated to discharge the second 10 missile. Thus, the missiles in the double arrangement are projected successively at the rate desired.

In Fig. 5 the construction is generally the same as that shown in Fig. 1 with the exception that a 15 tension spring 60 is employed instead of a compression spring and is provided with a hook 62 for engagement about the trigger 16. A suitable pin 63 supports the opposite end of the tension spring in an opening 65 that is plugged at one end, as indicated at 66.

Referring to Fig. 6, a single missile toy 67 is provided which is substantially the same in construction as that shown in Figs. 3 and 4 with the exception that one trigger 39 and one spring finger 57 are omitted. Hence, like reference characters are employed and the description corresponds to that already set forth above.

Although only the preferred forms of the invention have been shown and described in detail 30 it will be apparent to those skilled in the art that the invention is not so limited but that various changes may be made therein without departing from the spirit of the invention or from the scope of the appended claims.

35 What is claimed is:

1. A toy gun comprising a barrel portion recessed at its outer end portion for anchoring a missile, said barrel portion having an inclined slot adjacent its other end, a trigger pivoted 40 upon the toy in the slot, and resilient means for urging the upper end portion of the trigger against the rear wall of the slot to hold the missile between the trigger and rear wall preparatory to projecting it from the gun by pressing the trigger.

2. A toy gun comprising a barrel portion and a handle portion, the front end of the barrel portion having a transverse recess and a longitudinal recess intersecting to provide anchoring 50 means for a T-shaped missile, a trigger mounted adjacent the rear end of the barrel portion, the upper end of the trigger being inclined rearwardly, an abutment adjacent the junction of the barrel and handle portion for receiving the upper end of the trigger, and resilient means for urging the upper end of the trigger rearwardly toward said abutment to grip the missile preparatory to discharging it by pressing the trigger.

3. A toy gun adapted to discharge a headed 60 elastic missile comprising a barrel portion and a handle portion, said barrel portion having a plurality of intersecting recesses at its outer end for receiving and anchoring the headed portion of the elastic missile, a trigger pivoted in the 65 body of the toy adjacent the junction of the barrel and handle portion, a trigger abutment formed by recessing a portion of the gun adja-

cent the junction of the barrel and handle portion and a spring in the body of the gun having one end normally urging the trigger to force its upper end rearwardly against the trigger abutment to clamp the end of the elastic missile preparatory to discharging it. 80

4. A toy gun comprising a barrel and handle portions, a trigger mounted in the gun adjacent one end of the barrel portion, and a trigger guard having a spring portion bearing against the trigger tending to move it in one direction to clamp a missile against a portion of the gun preparatory to discharging it. 85

5. A toy gun comprising a body having a trigger movably mounted therein, a strip of material for guarding the trigger and having a resilient portion extending into contact with the trigger and normally urging one end of the trigger to form a clamp with an adjacent portion of the body whereby the elastic missile can be held in clamped relation until the trigger is pressed for discharging it. 90

6. A toy gun comprising a body, a pair of triggers pivotally mounted in the body, said body having an abutment for limiting pivotal movement of each trigger in one direction and a trigger guard disposed about portions of the trigger and having resilient extensions normally engaging the triggers to urge them toward their respective limiting abutments. 95

7. A toy gun adapted to discharge a plurality of headed elastic missiles comprising a barrel portion and a handle portion, said barrel portion having a plurality of intersecting recesses at its outer end for receiving and anchoring the headed portions of the plurality of elastic missiles, a pair of triggers pivotally mounted adjacent the junction of the barrel and handle portion, said triggers being disposed at angles to each other, a pair of trigger abutments on the body of the gun adjacent the upper ends of the trigger to limit movement thereof in one direction, and resilient means for urging the upper end of each trigger rearwardly toward its limiting abutment to clamp one end of the elastic missile between said upper end of the trigger and abutment preparatory to discharging it. 105

8. A toy gun adapted to discharge a plurality of elastic missiles having T-shaped end portions comprising a barrel portion and a handle portion, said barrel portion having a plurality of intersecting recesses at its end for receiving and anchoring the T-shaped portions of the plurality of elastic missiles, a pair of triggers pivotally mounted adjacent the junction of the barrel and handle portions, said triggers being disposed at angles to each other, a pair of trigger abutments on the body of the gun adjacent the upper end of the trigger to limit movement thereof in one direction, and a trigger guard having its opposite end portions formed into spring members engaging the respective triggers to urge them toward their limiting abutments for clamping end portions of the elastic missiles. 115
